INVENTOR
WM. R. MACKLIND

ATTORNEY

By *John B. Billman*

UNITED STATES PATENT OFFICE.

WILLIAM R. MACKLIND, OF CHICAGO, ILLINOIS.

FURNACE.

Application filed January 24, 1920. Serial No. 353,706.

To all whom it may concern:

Be it known that I, WILLIAM R. MACKLIND, a citizen of the United States, residing at Chicago, in the county of Cook and State of Illinois, have invented certain new and useful Improvements in Furnaces, of which the following is a specification.

My invention relates to improvements in furnaces, and more particularly to that class or type known as continuous rotary furnaces, the present embodiment being also of the "muffle furnace" type, and being particularly designed and adapted for treating lithopone.

15 The primary object of the invention is to provide a generally improved furnace of this class or type, which will be exceedingly simple in construction, cheap of manufacture, and efficient in use.

20 A further and very important object of the invention is the provision of an improved rotary continuously operating muffle furnace having an improved rotary drum or cylinder provided with an improved axially located treating tube projecting from the ends thereof and having improved heat creating and discharging heads independently supported and movable toward and from the ends of said rotary drum and 25 surrounding the ends of said projecting tube, together with improved means of hermetically sealing the joints between the ends of the rotary drum and heads and between the latter and the receiving and dis- 30 charging ends of the treating tube.

35 A still further object is the provision of material feeding and discharging compartments or chambers provided with improved material feeding and discharging mechanism communicating with the feed and discharge portions of treating tube independently of said rotary drum and heat creating and discharging heads and adapted when filled with material and in operation 40 to hermetically seal the opening or treating chamber in said treating tube, this being of particular importance in the treatment of lithopone so that the latter may be kept free from oxygen during treatment.

45 50 A still further object is the provision of a furnace wherein the material being treated may be subjected to any desired temperature and such temperature readily regulated and controlled, as well as indicated through the medium of an improved

pyrometer tube at the discharge end of the axial treating tube and provided with a pyrometer recording dial.

A still further object is the provision of improved heat insulated heat creating and discharging heads mounted independently of the rotary drum and treating tube and divided longitudinally at their center whereby the same may be readily taken apart for inspection, repair, or the like.

55 A still further object is the provision of improved material feeding mechanism at the ends of the material treating tube, together with improved means of inspecting the material therein while being treated.

60 With the above mentioned and other ends in view, the invention consists in the novel construction, arrangement and combination of parts, illustrated in one of its embodiments in the accompanying drawings, and particularly pointed out in the appended claims.

65 Referring to the drawings, forming a part of this specification, Figure 1, is a central longitudinal sectional view of a furnace constructed in accordance with this invention.

70 Fig. 2, a cross sectional view taken on line 2—2 of Fig. 1.

75 Fig. 3, a cross sectional view taken on line 3—3 of Fig. 1.

80 Fig. 4, a cross sectional view taken on line 4—4 of Fig. 1.

85 Fig. 5, a top plan view of the improved furnace.

90 Fig. 6, an enlarged detail view of the joint between the heat transmitting elements or sections making up the improved axial treating tube in the rotary drum.

95 Fig. 7, a fragmentary cross sectional view of the receiving end of the treating tube and illustrating the manner of securing the outer heat transmitting elements to the tubular reinforcing member of the treating tube above the combustion chamber of the furnace head.

100 Fig. 8, a fragmentary perspective view of the drum flues and baffle members of the improved rotary drum.

105 Similar numerals of reference designate like parts throughout all the figures of the drawings.

110 The improved furnace comprises a rotary drum or cylinder 1, made up of a surrounding shell of protecting material 1, and a

plurality of heat resisting elements 1^a, separated by means of baffle elements 1^b, and supporting elements 1^c, forming longitudinal flues 1^d, and interposed passages 1^e, 5 adapted to give the heat or products of combustion a zigzag course, as hereinafter explained.

The rotary drum or cylinder 1, is provided with an axial treating tube 2, having its receiving and discharging ends extending or projecting beyond the ends of the drum or cylinder 1.

The baffle elements 1^b, and flues 1^d, are adapted to be cleaned through the medium 15 of clean-out openings 1^f, closed by means of suitable caps or covers 1^g.

The receiving end of the axial treating tube 2, is provided with a tubular reinforcement 2^a to which the interior and exterior 20 elements 2^b and 2^c, respectively, are secured, the exterior tubular elements 2^c, being adapted to be secured by means of dovetailed elements 2^d, as will be most clear upon reference to Fig. 7, of the drawings.

25 The other or discharge end of the treating tube 2, is provided with a tubular reinforcing element 2^e, the latter being provided with inner and outer heat transmitting elements 2^f.

30 The intermediate or main body portion of the tube 2, is preferably made up of abutting tubular sections 2^g, said sections 2^g, as likewise the elements 2^b, 2^c and 2^f, being preferably formed of fire brick or other 35 good heat conducting material.

As a means of independently supporting and driving the rotary drum 1, and the treating tube 2, and also mounting the same in a slightly inclined manner from the feed 40 to the discharge end thereof, the drum or cylinder 1, is provided with circular or ring track members 3, adapted to ride upon and be supported by pairs of guide rollers or wheels 4, the latter being carried by shafts 45 5, and the shafts 5, being supported in bearings 5^a, resting on supports 5^b.

As a means of driving the rotary drum, the latter is provided with a gear ring 6, meshing with a gear wheel 7, the latter being 50 mounted on one of the shafts 5, and receiving its motion from a second gear wheel 8, and the gear wheel 8, receiving its motion from a shaft 9, driven from a suitable motor 10.

55 As a means of generating and passing a suitable heating fluid through the drum or cylinder 1, about the tubular treating member 2, during the rotation of the latter and said drum, heat creating and discharging heads 11 and 12, respectively, are mounted at the ends of the revolving drum and independently of the latter, and as a means of permitting of the ready opening and closing of the drum ends for inspection or 60 65 pair of the latter, as likewise for the inspec-

tion and repair of the treating tube 2, the heads 11 and 12 are longitudinally movable toward and from the ends of the drum 1, by being independently supported, said supporting means, in the present instance, comprising supports 11^a, and 12^a, respectively, 70 slideable on the main support 13, which latter is also adapted to support the working parts of the drum or cylinder 1, and the feeding and discharging members or compartments, hereinafter referred to. 75

The heat creating and discharging heads 11 and 12, respectively, are provided with openings 11^b and 12^b, respectively, adapted to loosely receive and contain the projecting ends of the treating tube 2. 80

The heads 11 and 12, are preferably surrounded by means of heat insulating material 11^c and 12^c, respectively, and the latter is preferably covered with a metallic covering 11^d and 12^d, as shown most clearly in Fig. 2 of the drawings. 85

As a means of separating the heads 11 and 12, transversely, for inspection or repair of the parts, said heads are divided centrally 90 and longitudinally, as at 14, said parts being adapted to be detachably held together by means of the flange members 14^a, and any suitable and convenient attaching elements. 95

The heat creating or generating head 11, is provided with a suitable combustion 11^e, the products of combustion being adapted to pass upwardly from such chamber 11^e, and through the flues 1^d, being diverted by 100 the baffle elements 1^b, to take a somewhat zigzag course and passing outwardly into the discharge chamber 12^e, of the heat discharging head 12. 105

The heating fluid is adapted to pass out of the heat flue 15, and may be controlled by means of the damper 15^a.

As a means of hermetically sealing the joints between the ends of the drum or cylinder 1, and the heads 11 and 12, the latter are 110 provided with annular seal plates 16, adapted to resiliently contact with and bear against annular drum seal flanges or wear plates 17.

As a means of similarly sealing the openings 11^b and 12^b, around the receiving and discharging ends of the treating tube 2, the tubular feed extensions 2^h, of the treating tube 2, are provided with similar annular seal plates 18. 115

As a means of conveniently feeding the material, such for example, as lithopone, to and from the feed and discharge ends of the treating tube 2, suitable material feeding and discharging members or receptacles 19 and 20, respectively, are connected to the extensions 2^h, of the treating tube, the feeding receptacle 19, in the present instance, forming a storage bin or chamber, the latter being supplied by means of a feed pipe 19^a. 120 125 130

The feed of the material from the bin or receptacle 19, may be regulated and controlled by means of a feeding roller 19^b, driven by a shaft provided with a pulley 5 19^c.

The material passing from the feed roller 19^b, is adapted to be fed into the feed end of the treating tube by means of the feed screw 21, mounted on a tubular member 21^a, 10 and driven by a pulley 22. The tube 21^a, is provided at its end with a cap 23, and by removing the latter the condition of the material being operated upon in the treating tube 2, may be observed.

15 As a means of discharging the material from the discharge end of the treating tube the latter is provided with a discharging screw 24, mounted on a tubular member 24^a, the latter extending through the discharging member 20, and being adapted to be driven by a suitable pulley 25. The tubular member 24, may be opened and closed by means of a cap 26, and as a means of determining the temperature with 20 25 in the treating tube the tubular member 24, is provided with a pyrometer tube 27, having a suitable connection with a pyrometer recording dial 28. The discharging receptacle or housing 20, is provided, in the present instance, with a flue or stack 29, provided with a damper or valve 29^a, for the control of the gases arising from the discharging material into the chamber of the discharge receptacle 20.

35 As a means of hermetically sealing the ends of the treating tube 2, the treated material 30, is adapted to accumulate in the supply and discharge receptacles (this being regulated by regulating the feed and discharge screws or mechanism), as indicated by the stippled lines in Fig. 1, of the drawings.

In the treatment of a material such as lithopone, the chamber of the receptacle 20, 45 is preferably reduced and the material is adapted to accumulate therein, as indicated, to seal the same, and is adapted to be discharged by means of a screw 31, operating on a vertical shaft 32, the latter extending 50 through a cone shaped quenching tank 33. The shaft 32, is provided with an agitator 34, operating in the water in the quenching tank 33 in order to keep the material in a flowing condition, the water being permitted 55 to pass out through the overflow pipe 35, and thus being prevented from arising by means of the submerged baffle 36.

As a means of discharging the material through the discharge openings 37, the extreme lower end of the shaft 32, is provided 60 with a screw 38, the shaft 32, receiving its motion through bevel gears 39, one of the latter being connected to a shaft 40, and being driven by a pulley 41.

65 The top of the quenching tank 33, is pro-

vided with vent pipes 42, and the tank 33, may be filled with water through the medium of the inlet opening 43.

From the foregoing description, taken in connection with the accompanying drawings, 70 the operation and advantages of my invention will be readily understood.

Having thus described one of the embodiments of my invention, without having attempted to set forth all the forms in which 75 it may be made, or all the modes of its use, what I claim and desire to secure by Letters Patent, is,—

1. In a furnace, the combination with a rotary drum provided at its ends with annular flange members; of longitudinally divided heat creating and discharging heads movable transversely toward and from the ends of said drum and provided with annular sealing members slidably and resiliently 80 engaging and sealing said annular flange.

2. In a muffle furnace, a rotary horizontal drum, an axial heat transmitting treating tube therein, means for feeding material into one end of said treating tube, a discharge 90 head at the opposite end of said treating tube, and means within said discharge head for discharging the material from said treating tube and sealing the latter with the material discharged. 95

3. In a muffle furnace, a rotary horizontal drum, an axial heat transmitting treating tube therein, means for feeding material into said tube, a discharge receptacle provided with a chamber at the opposite end of said 100 treating tube, and means within said chamber for discharging the material from the discharge end of said treating tube and sealing the latter with the material being discharged. 105

4. In a muffle furnace, a rotary horizontal drum, an axial heat transmitting treating tube therein, a feed hopper provided with feed mechanism discharging the material into said treating tube, a discharge head provided with a chamber communicating with the discharge end of said treating tube, and means for discharging the material from the discharge end of said tube and sealing the latter with the material being discharged. 110 115

5. In a furnace, an axial treating tube having its receiving and discharging ends provided with tubular metallic reinforcements and inner and outer heat transmitting elements, and its intermediate portions made up of a plurality of abutting tubular heat transmitting sections. 120

6. In a furnace, the combination with a heat insulated rotary drum provided with 125 flues and baffles and a central treating tube; of longitudinally divided heat creating and discharging heads including sections movable transversely to open and close the ends of said drum provided with annular sealing 130

members slidably engaging and sealing the ends of said drum and treating tube.

7. In a furnace, the combination with an independently supported and driven rotary heat insulated drum provided with an axial treating tube projecting from the ends thereof; of independently supported longitudinally split transversely movable two-part heat creating and discharging heads surrounding the projecting ends of said treating tube and movable toward and from the ends of said treating tube and rotary drum to seal and unseal the same.

8. In a furnace, the combination with a heat insulated rotary drum provided with an axial treating tube having its ends projecting from the ends of said drum; of two-part heat creating and discharging heads including sections transversely movable toward and from the ends of said drum and surrounding the ends of said tube, the ports of said two-part heads being detachably connected longitudinally for movement toward and from each other relative to said treating tube ends independently of said movements toward and from said drum ends.

9. A furnace, comprising a rotary horizontal drum, an axial treating tube therein and projecting from the ends thereof, a two-part head provided with a combustion and heating chamber at one end of said tube and drum adapted to pass the products of combustion through said drum and about said treating tube, means for feeding material into said tube independently of said movable head, a movable heat discharge head at the opposite end of said tube and drum, and means for discharging material from the discharge end of said tube.

10. A furnace, comprising a rotary horizontally inclined drum, an axial heat transmitting treating tube therein and projecting therefrom; a movable head provided with a combustion chamber surrounding said tube and adapted to pass the products of combustion through said drum and about said treating tube, means for feeding material into said tube and sealing the latter with the feeding material, a discharge chamber at the opposite end of said tube and provided with a quenching chamber, and means for discharging material from the discharge end of said tube into said discharge chamber and from the latter into said quenching chamber.

11. In a muffle furnace, a rotary horizontal drum provided with flues and baffles and an axial treating tube therein and projecting therefrom, an insulated head provided with a combustion chamber surrounding said tube and divided into sections transversely movable to close and seal said drum and pass the products of combustion through said flues and over said treating tube, a feed

hopper provided with a mechanism discharging material into and hermetically sealing said treating tube, a second insulated head surrounding the opposite end of said treating tube and receiving the products of combustion from said drum, and discharge and muffle chambers communicating with said treating tube and sealing the latter with the material being discharged.

12. In a muffle furnace, a rotary horizontal drum provided with longitudinally extending flues and transversely extending baffles, an axial treating tube therein and projecting from opposite ends thereof, a head provided with a combustion chamber surrounding said tube and divided into sections transversely movable toward and from said drum and adapted to pass the products of combustion through said flues and about said treating tube, a feed hopper in front of said head and provided with a feed screw discharging the material into said treating tube, a second head at the opposite end of said drum and surrounding said treating tube to receive the products of combustion therefrom, and a discharge chamber communicating with the discharge end of said treating tube and adapted to seal the latter when filled with material.

13. In a muffle furnace, a rotary horizontal drum, an axial heat transmitting treating tube therein, a head provided with a combustion chamber surrounding said tube and adapted to pass the products of combustion thru said drum and about said treating tube, a feed hopper in front of said head and provided with feed mechanism discharging the material into said treating tube, a discharge head provided with a chamber communicating with the discharge end of said treating tube, and means for discharging the material from the discharge end of said tube and sealing the latter with the material being discharged.

14. A muffle furnace, comprising a rotary horizontal drum, an axial heat transmitting treating tube therein and projecting therefrom, a head provided with a combustion chamber surrounding said tube and adapted to pass the products of combustion thru said drum and over said treating tube, means for feeding material into said tube, a second head surrounding the opposite end of said treating tube, a discharge receptacle provided with a chamber at the opposite end of said treating tube, and means within said chamber for discharging the material from the discharge end of said treating tube and sealing the latter with the material being discharged.

In testimony whereof I have affixed my signature.

WILLIAM R. MACKLIND.
